UNITED STATES PATENT OFFICE.

HENRY J. MEREDITH, OF HOLYOKE, MASSACHUSETTS.

TELEPHONE SYSTEM.

1,188,002.

Specification of Letters Patent. Patented June 20, 1916.

Application filed February 6, 1915. Serial No. 6,533.

To all whom it may concern:

Be it known that I, HENRY J. MEREDITH, a citizen of the United States, residing at Holyoke, in the county of Hampden, and State of Massachusetts, have invented certain new and useful Improvements in Telephone Systems, of which the following is a specification, reference being had to the accompanying drawings.

10 My invention relates to telephone systems, and particularly to a telephone system wherein an alternating instead of a direct current is used.

The primary object of my invention is to 15 so arrange the system that an alternating current may be used for the purpose of transmitting sound telephonically, and thus the distance over which sound may be transmitted may be greatly increased, without, 20 however, diminishing the sound received by the receiver, but on the other hand, increasing the distinctness of the transmitted sound.

A further object of the invention is to 25 provide for stepping down the voltage of the current received from the source of power to the proper voltage for the transmitter and stepping up this voltage to that proper to be used in the receiver, and also 30 step up the voltage when it is desired to increase the length of the line so as to transmit sound to greater distances.

A further object is to provide for continuous self-induction throughout the entire telephone system and in the transformer 35 connections on the principle of a choke coil so that the current in the primary circuit shall vary directly as the load on the secondary.

Still another object is to provide means 40 for dampening or quieting the transmission by the use of condensers connected in multiple with the primary or secondary coils of the transformer used for stepping down the voltage of the alternating current.

45 Other objects will appear in the course of the following description.

My invention is illustrated in the accompanying drawings, wherein—

Figure 1 is a diagram of a telephone system arranged in accordance with my invention; Fig. 2 is a like view to Fig. 1, showing the use of condensers; Fig. 3 is a diagram showing a different arrangement of the telephone circuit; Fig. 4 is a diagram 55 showing a telephone system wherein power is secured from a plurality of currents; Fig.

5 is a diagrammatic view showing my system applied where one transmitter is used with a plurality of receivers; Fig. 6 is a diagrammatic view showing another arrangement of the system, and Fig. 7 is a diagram showing a different means for controlling the voltage of currents passing over the circuit.

Referring now to Fig. 1, 2 designates the 65 wires or conductors leading from a source of low frequency, single phase alternating current to the primary coil 3 of a transformer whose secondary winding or coil is designated 4. An adjustable core 5 is used 70 in the transformer, which is adjustable so as to control the current induced in the secondary winding of said transformer. This core is preferably laminated. It is to be understood that this transformer may be 75 of any suitable character, and that I have only illustrated it diagrammatically. Leading from the secondary coil of the transformer are the conductors 6—6 forming a 80 secondary circuit in which is included the primary winding 7 of a transformer 8, and also included in said circuit is the transmitter 9. The secondary coil 10 of the transformer 8 is connected in circuit with a receiver 11 of any suitable character. The line 85 wires 12 are connected in multiple with the secondary circuit 6—6 and a transmitter 13, and the primary winding 14 of a transformer 15 is also connected in multiple with the line wires 7—7. Coacting with the 90 primary winding 14 of the transformer 15 is the secondary winding 16 connected in circuit with the receiver 17.

It will be understood that the voltage of the alternating current in the wires 6—6 is 95 lower than the voltage in the wires 2—2, through this current being stepped down by the transformer 3, 4 and 5, and that this current is stepped up by the transformer 8 so that it may be used to actuate the receiver where a relatively high degree of voltage is required.

In Fig. 2 I show a circuit arrangement practically similar to that shown in Fig. 1, but in which the primary wires of the 100 transformer 1 connected with the source of energy are connected in multiple with the condenser 18. I may connect one or more condensers in multiple in circuit with the source of energy transformer, as previously 105 described, across the primary leads of the transformer. Also in Fig. 2 I show a con-

denser 19 connected across the line wires 6-6. I may use one or more condensers connected in multiple, however. It is not essential that these condensers in Fig. 2 be used under all circumstances, their use depending on the requirements of the system.

In Fig. 3 I show a circuit 20 including a secondary 21 of a transformer 22, the primary coil of which is connected to a source 10 of alternating current, this circuit also including in it a plurality of primary transformer coils 23 and a transmitter 24. Coacting with each of the primary coils 23 of the step up transformers is a receiver circuit 15 having therein the secondary coil 25 of the transformer. It will be seen that the principle of this arrangement is precisely the same as the principle illustrated in Fig. 1.

In Fig. 4 I show a telephone circuit so 20 arranged that it receives energy at a plurality of points in the system. Thus in this figure, 26, 26^a and 26^b designate the primary windings of a plurality of step down transformers, each of these primary windings being connected with a source of alternating current. The secondary windings 27^a and 27^b of the transformers 26^a and 26^b are each connected in circuit with a transmitter 28 and with the primary coil 29 of 25 a transformer whose secondary coil 30 is in circuit with the receivers 31. The primary coil 26 coacts with the secondary coil 27 in circuit with a transmitter 28 and a primary coil 32 of a transformer whose secondary 33 is connected in circuit with the coil 30 and the receivers 31. A condenser 34 is also interposed in the circuit, as illustrated in Fig. 4 and for the purpose heretofore described.

In Fig. 5 I show a system wherein the receivers 35 (as shown in full lines) are connected in series with the secondary winding 36 of a transformer whose primary winding 37 is connected in circuit with the transmitter and with the secondary of a step 40 down transformer 38 having an adjustable core, as described in Figs. 1 and 2. In dotted lines in Fig. 5 I show that the receivers 35 might be connected in multiple as well as in series, as I do not wish to be 45 limited to the use of the receivers in series.

In Fig. 6 another arrangement is illustrated wherein signals are arranged in connection with each telephone. In this figure 40 designates the primary winding of a 45 transformer connected with a source of alternating current, and 41 designates the secondary winding thereof. This secondary winding is connected in circuit with the primary winding 42 of a transformer whose 50 secondary winding is connected in circuit with the receiver 43. Also disposed in this circuit is a transmitter 44, and the circuit is normally broken by a hook switch 45. This 55 hook switch normally connects the secondary 41 in circuit with a signal bell 46, in

turn connected to a ground, the other side of the coil 41 being connected to a ground 47, there being a signal lamp disposed also in this circuit. Instead of grounding the circuit, however, a return conductor 48 70 might be used, which is illustrated in dotted lines. I have also illustrated in this figure a second circuit connected with the first and operating in the same manner.

In Fig. 7 I show an arrangement whereby 75 the volume of the transmitted energy may be increased without shifting the coil of the transformer. In this connection the secondary coil 50 of the transformer, whose primary coil is designated 51, has a plurality 80 of taps or connections 52, each leading from a different point of the coil. The conductor 53 of the line is connected with an adjustable arm 54 or switch which may be shifted into electrical engagement with any one of 85 the taps, thereby using a part of the coil as reactance, according to the exigencies of the situation.

It will be noted that a continuation of the transforming of the current either by stepping the current up or stepping it down will carry the sound waves to a greater distance. Thus in Fig. 7 I have shown the line wires 55 as running to a primary 56 of a transformer, the secondary 57 of which is connected with the primary winding 58 of a transformer whose secondary 59 is connected to line wires 60.

While I have illustrated many diagrams showing different arrangements of my system, it will be seen that in all these diagrams the same principle of operation is used, and that in all the systems illustrated continuous self-induction is produced, and throughout all the systems the step down and step up 105 transformers are used for the purpose of increasing or decreasing the voltage of the current. It will also be seen that by the use of the extra step up transformers I am able to transmit a further distance than 110 could otherwise be attained, and that in this case the primary of the extra step up transformer is in circuit with the secondary of the first step up transformer, while the secondary of the extra step up transformer is 115 connected to the line. It will be seen that with my telephone system it is not required that the energy be derived from a primary or secondary battery in the transmitter circuit. Instead it is the alternating current 120 which is varied throughout the entire length of the circuit by the action of the transmitter.

It is to be noted that self induction is always present where a choke coil is connected in circuit with an alternating current. If a choke coil is placed in circuit with an alternating current, as illustrated in the diagrams previously described, it produces a lagging effect on the current. Thus these 125 130

transformers tend to react on each other and quiet the heavy buzzing which would be otherwise present. The two choke coils are in series, one as the secondary of the transformer connected with the source of energy and the other as the primary of the second or step up transformer, thus producing continuous self induction which tends to carry the current in the circuit a longer time than without these coils and makes a smoother current wave and one not so abrupt.

It is very necessary in my circuit arrangement that the windings of the several transformer coils bear a direct relation to one another. Thus the winding of the primary on the transformer used in connection with the source of energy must be in correct ratio to the winding of the secondary coil of this transformer and the winding of this secondary coil must in turn be such that the proper reactance is secured in the secondary circuit in which are one of the transmitters and the primary winding of the step-up transformer. The reactance and proper winding of this step-up transformer act together to prevent the heavy buzzing that would be present unless the proper relation of these transformer windings and their cores is secured. Now the transmitter, by reason of its being connected directly in a low voltage circuit, varies the low voltage reactance wave and the primary coil of the step-up transformer being in circuit with the transmitter and the secondary winding of the transformer connected to the source of energy, varies this reactance wave and this variance has its effect on the current induced in the secondary winding of the step-up transformer, in which secondary winding is the receiver. This secures a heavy volume of sound in the receiver.

While the transmitter and receiver might be connected in circuit with the secondary of the transformer connected with the source of energy, yet such connection would limit the range of transmission of the telephonic current. By placing the transformer in circuit as heretofore described, and as illustrated in the diagrammatic views, I am able to vary the entire current flowing into two transformers and secure the reactance effect of the two choke coils thus smoothing the current wave and giving a good volume of sound in the receivers, which in turn is governed by the amount of reactance controlled by moving the core of the secondary of the transformer connected to the source of energy, or by moving the secondary winding itself, or both the core and the secondary winding, or in the manner illustrated in Fig. 7.

It will be of course obvious that the object of using one transmitter with a number of receivers connected either in series or multi-plex as in Fig. 3, is to permit the trans-

mission of the voice to many places at the same time. Thus the system illustrated in Fig. 5 or that illustrated in Fig. 3 may be used for announcing purposes in large halls and public places, as in railroad stations and in trains. My telephone system may be used in ordinary telephone practice of any description, and with any circuit arrangement carrying out the principles illustrated in the diagram.

It is to be understood that the coil or step up transformer in use in Fig. 7 as an extra transformer may also be used in connection with any of the systems illustrated in the several diagrams, and is not limited in this use to the system illustrated in Fig. 7.

Having described my invention, what I claim is:

1. In a telephone system, a step down transformer having its primary winding connected in circuit with a source of low frequency alternating current, a step up transformer having its primary winding in circuit with the secondary winding of the first named transformer, a transmitter in said circuit, a receiver in circuit with the secondary winding of the said second named transformer, and condensers connected in multiple across said first two circuits. 90

2. A telephone system comprising a plurality of circuits, one of which includes a transmitter, a step-down transformer, whose primary is connected to a source of low-frequency alternating current energy, the step-down secondary winding supplying voltage 100 of the proper value for the transmitter circuit, a step-up transformer whose primary is connected in series with the transmitter circuit and the step-down secondary winding, the secondary step-up winding of the second 105 transformer being adapted to step-up the voltage in a circuit which includes a receiver.

3. A telephone system comprising a source of low-frequency electric energy, a variable magnetic circuit static transformer adapted to supply energy at a uniform value to a talking circuit including a transmitter and directly connected to the primary of another static transformer, the secondary of which includes a receiver, the cooperative relation 110 established between the several transformers tending to amid the sound of current reversals and to amplify the transmitted current wave at the receiving end, and a condenser connected in multiple with one of the outer terminals of a primary winding, and a secondary winding respectively in the talking circuit. 115

4. A telephone system comprising a source of electric energy, a variable magnetic circuit static transformer adapted to supply energy at a uniform value to a talking circuit including a transmitter and directly connected to the primary of another static transformer, the secondary of which in- 120 125 130

eludes a receiver, the several transformers when directly connected through connecting lines operating to prevent leakage, and a capacity in shunt with the transmitter.

5. In a telephone system, the combination with a source of alternating current, associated with the primary winding of a variable magnetic circuit static transformer, of a plurality of circuits, a secondary winding 10 inductively connected to said transformer

and a circuit in series with the primary winding of another static transformer, a condenser in multiple with said circuit, and a transmitter in said circuit.

In testimony whereof I hereunto affix my 15 signature in the presence of two witnesses.

HENRY J. MEREDITH.
